(57) CLAIM

I claim the ornamental design for a cover, as shown and described.

DESCRIPTION

FIG. 1 is a perspective view of a first embodiment cover, in accordance with the present invention;

FIG. 2 is a bottom plan view of the cover shown in FIG. 1;

FIG. 3 is a top plan view of the cover shown in FIG. 1;

FIG. 4 is a left side view of the cover shown in FIG. 1;

FIG. 5 is a right side view of the cover shown in FIG. 1;

FIG. 6 is a front plan view of the cover shown in FIG. 1;

FIG. 7 is a back plan view of the cover shown in FIG. 1;

FIG. 8 is a perspective view of a second embodiment cover, in accordance with the present invention;

FIG. 9 is a bottom plan view of the cover shown in FIG. 8;

FIG. 10 is a top plan view of the cover shown in FIG. 8;

FIG. 11 is a left side view of the cover shown in FIG. 8;

FIG. 12 is a right side view of the cover shown in FIG. 8;

FIG. 13 is a front plan view of the cover shown in FIG. 8; and,

FIG. 14 is a back plan view of the cover shown in FIG. 8.

In the drawings, the broken lines depict a central structure and four holes that form no part of the claim.

1 Claim, 14 Drawing Sheets
